TUNING MECHANISM FOR A STRING MUSICAL INSTRUMENT

Norval P. Ulrich, 1203 Carrie, Des Moines 9, Iowa
Filed Aug. 27, 1963, Ser. No. 304,996
9 Claims. (Cl. 84—312)

This invention relates generally to string musical instruments, and more particularly to such instruments as the guitar, mandolin, banjo and the like, although not limited thereto, which are played by picking or stroking the strings.

An object of this invention is to provide a stringed instrument on which one or more or several chords can be played without resort to difficult fingering operations which can otherwise be performed only by skilled performers thus making it possible for players having only rudimentary skill to give performances comparable to the performances of players of such greater experience and accomplishment.

To the above end, the stringed instrument disclosed herein is provided with a mechanism for each string which may be remotely actuated, as by movement of the player's foot, to automatically vary the tension of the string a predetermined amount. By providing each string of the instrument with such a mechanism, whereby the tension of each string may be varied to any one of several quantities when several strings are stroked a definite predetermined chord is produced. Thus, no particular musical skill is required to play any chord the instrument has been previously set to produce.

The invention contemplates the addition to an otherwise more or less conventional stringed instrument of a mechanism for each string, and of a plurality of foot operated electric switches for each mechanism, whereby actuation of any one switch results in the mechanism operating to effect a predetermined degree of tension on the string.

It is, therefore, an object of this invention to provide an improved automatic chord tuning mechanism for a string musical instrument.

It is another object of this invention to provide a chord tuning mechanism having a structure automatically responsive to remotely operable means for varying the tension of a string from one degree to a predetermined one of several other degrees of tension.

Yet another object of this invention is to provide a chord tuning mechanism for selectively varying the tension of all or any combination of strings of a string instrument so that certain strings are tightened while others are slackened, all in response to a single operation of a common actuating member, such as, for example, a foot pedal.

Still another object of this invention is to provide a chord tuning mechanism for each string of a string instrument wherein a rocker arm is operable to vary the tension on a string in response to movement of a shaft, the shaft automatically started and stopped as to its movement due to electric coaction of a pair of solenoids and a plurality of electric switches selectively engageable by said shaft.

It is another object of this invention to provide a chord tuning mechanism for a string instrument capable of attaining said above mentioned objects, and which is economical to manufacture, effective in operation, and easily serviced.

These objects, and other features and advantages of this invention will become readily apparent from the following description when taken into consideration with the accompanying drawings, wherein:

FIG. 1 is a side elevational view of a schematic nature of the chord tuning mechanism of this invention, in assembled relation for one string;

2

FIG. 2 is a view similar to FIG. 1 showing the mechanism in a different position wherin the tension of the string is varied over FIG. 1;

FIGS. 3, 4, and 5 are enlarged side elevational views of one electric switch in three different positions due to action with a switch block; and

FIG. 6 is a diagrammatic view of the electric circuit for the single string, chord tuning mechanism of FIG. 1.

Referring now to the drawings, a fragment of a single 10 musical string 10 is shown in FIGS. 1 and 2. The string 10 is but one of several strings, six for example of a conventional stringed instrument having a sounding board supported by legs or the like at a predetermined height above a floor. The strings 10 are stretched lengthwise 15 of the sounding board in an overlying manner due to a pair of bridges secured to the board in longitudinal spaced relation. Each string 10 is attached at one end to a tuning key of a type ordinarily provided on guitars and other similarly stringed instruments. The string 10 is thus tuned in a conventional manner by turning the tuning key.

With this conventional arrangement in mind, applicant's 20 apparatus for automatically varying the degree of tension on the string 10 along or in combination with other strings is indicated generally at 11 in FIGS. 1 and 2. The string 10 is connected, at the end opposite the tuning key, to the upper end 12 of a tension adjusting bar 13. A notch 14 is formed in one side of the upper end 12 for receiving the pointed end of a stationary fulcrum 16 about 25 which the adjusting bar 13 is adapted to rock. A spring 17 is secured between the upper end 12 and a bolt 18 threaded through a nut 19 and a stationary plate 21 for providing a fine, vernier-type adjustment on the string 10 via the adjusting bar upper end 12.

Integral with the upper end 12 of the adjustment bar 13, a lower end 22 depends angularly away therefrom and is provided with a nylon wheel 23 rotatably mounted at the extreme end thereof. The wheel 23 is engageable with any one of a plurality, four for example, of tuning 30 adjustment knobs 24, 25, 26 and 27 which are threadably inserted through an elongated shaft 28 in longitudinal spaced relation. It is readily observed that the adjustment knobs protrude at varying extent, whereby upon engagement of the wheel 23 with one knob 27, for example, 35 the tension on the string 10 is considerably less than the tension thereon when the wheel 23 is engaging the knob 24 furthest from knob 27.

The adjustment knobs are secured to the shaft 28 intermediate a pair of separators 29 and 31 through which 40 the shaft extends for reciprocation between two pairs 32 and 33 of guides which extend at right angles to the longitudinal axis of the shaft 28. At the left end 34 of the shaft 28, as viewed in FIG. 1, are a pair of parallel arms 36 and 37 each of which is independently and 45 pivotally connected to the shaft end 34. A compression spring 38 is inserted between the arms 36 and 37 to maintain them in a spaced apart condition. A pair of limit pins 39 and 41 limit the placement of the arms 36 and 37.

50 In their normal condition, the arms 36 and 37 straddle in a non-engaging manner a drive member 42 which, when operating, rotates continually in the direction indicated by the arrow in FIG. 1. To selectively move either arm 36 or 37 into engagement with the drive member 42, a pair 55 of single-acting solenoids 43 and 44 are provided on opposite sides of the drive member 42 and on the outer sides of the arms 36 and 37. The respective plungers 46 and 47 of the solenoids are continually engaged with the arms 36 and 37, respectively.

60 As illustrated in FIG. 1, when the upper solenoid 43 is momentarily energized in a manner hereinafter described, the plunger 46 of the solenoid 43 is extended to

force the arm 36 into engagement with the drive member 42. Rotation of the drive member 42 thus moves the arm 36 to the right as viewed in FIG. 1 which results in movement of the shaft 28 to the right. Should, conversely and subsequently to energization of the upper solenoid 43, the lower solenoid 44 be momentarily energized, its plunger 47 is extended to move the lower arm 37 into engagement with the drive member 42 (FIG. 2). Rotation of the drive member 42 in the direction indicated would therefore move the arm 37 to the left, which would result in movement of the reciprocal shaft 28 to the left, as viewed in FIG. 2.

At the right end 48 (FIG. 1) of the shaft 28, a control block 49 is provided which has a quartet of control faces 51, 52, 53 and 54 one face being formed at each corner of the rectangular block 49. Intermediate the inner and outer upper faces 51 and 52, a flap top surface 56 is provided, whereas a flat bottom surface 57 is provided on the control block 49 between the inner and outer lower faces 53 and 54. Disposed about the control block 49 in longitudinally spaced relation are a pair of normally closed electric switches 58 and 59 of the two leaf type and disposed above and below the control block 49 are a pair of three-leaf electric switches 61 and 62.

Referring now to the electric circuit for the chord tuning mechanism in FIG. 6, it is seen that the solenoids 43 and 44 are connected by a line 63 to one side of a source of electric current, with the other side of the source connected by a line 64 to a plurality, four for example, of normally open, on-off switches 66, 67, 68 and 69 arranged in parallel. Although not shown herein, it may readily be realized that these switches 66-69 are manually operable, as by the player's foot. The switch 69 is interconnected by a line 71 to a movable leaf 72 of the switch 59 with the stationary leaf 73 connected by a line 74 to the upper solenoid 43. The switch 68 is connected by a line 76 to the center movable leaf 77 of the switch 61, which is normally closed against a stationary leaf 78 connected in turn by a line 79 to the lower solenoid 44. The upper stationary leaf 81 of the switch 61 is connected via lines 82 and 74 to the upper solenoid 43.

Switch 67 is connected by a line 83 to the center movable leaf 84 of the lower switch 62, which leaf 84 is normally closed against the upper stationary leaf 86, connected in turn via lines 87 and 79 to the lower solenoid 44. The lower stationary leaf 88 is connected by a line 89 and the line 74 to the upper solenoid 43. The left-most switch 66 is connected, when closed, by a line 91 to the movable leaf 92 of the switch 58, with the stationary leaf 93 connected by lines 94 and 79 to the lower solenoid 44.

In operation of the chord tuning mechanism 11, assume that neither solenoid 43 and 44 is energized, wherefore neither arm 36 and 37 engages the driven member 42, that the shaft 28 is in the position of FIG. 2, and that the player of the instrument desires to change the tension on the string 10 to a degree accomplished by engaging the wheel 23 with the tuning adjustment knob 27.

It should be mentioned herein that the circuitry and structure of applicant's chord tuning mechanism, as demonstrated hereinafter, is such that upon closing the manually operated switch 66, the shaft 28 will move to engage the wheel 23 with the knob 27; upon closing the switch 67, the shaft will responsively move to engage the wheel 23 with the knob 26; upon closing the switch 68, the shaft 28 will be moved to place the knob 25 in engagement with the wheel 23; and upon momentarily closing the switch 69, energization of one of the solenoids will result in the drive member 42 moving the shaft 28 until the circuit is opened by operation of the switch 59, whereupon the movement of the shaft 28 stops with the knob 27 engaging the wheel 24.

Thus, upon closing the switch 66, current is transmitted through line 91 (FIG. 6) to the normally closed 75

leaf switch 58, where the current is then conducted through lines 94 and 79 to the lower solenoid 44. The solenoid 44 is energized to extend the plunger 47 whereupon the arm 37 (FIG. 2) is moved into engagement with the rotating drive member 42. Clockwise rotation by the member 42 thus pulls the arm 37 to the left in FIG. 2, also responsively moving the shaft 28 to the left.

As the various faces and surfaces of the control block 49 engage with and disengage from the movable leafs 84 and 77 of the switches 62 and 61, respectively, the circuit is not affected due to the respective foot-operated switches 67 and 68 therefore being open. However, during the movement of the shaft 28 to the left from its FIG. 2 position, the inner face 51 of the control block 49 eventually engages the movable leaf 92 (FIGS. 1 and 6) of the switch 58 and breaks its contact with the leaf 93.

This operation thus opens the circuit to the solenoid 44, whereupon the solenoid 44 is de-energized and the plunger 47 retracted. The spring 38 is operable to immediately move the arm 37 away from the drive member 42, and the shaft 28 is stopped with the knob 27 engaging the wheel 23, the rocker bar 13 accordingly pivoted counter-clockwise about the fulcrum 16, thus tightening the string 10.

Should it be desirable to slaken the tension on the string 10 slightly, for example to change the position of the bar 13 to one of engagement with the knob 25, the switch 68 is closed. Current is then conducted through the line 83 to the center, movable leaf 77 of the switch 61. As illustrated in FIGS. 1 and 3 the leaf 77, engaged with the upper surface 56 of the control block 49, is in contacting engagement with the upper leaf 81 (FIG. 6) of the switch. Current is therefore conducted through line 74 to the upper solenoid 43.

Energization of solenoid 43 extends the plunger 46 whereupon the arm 36 is moved into engagement with the drive member 42. The counter clockwise movement of the member 42 forces the shaft 28 to the right in FIG. 1. Referring to FIG. 4, it is seen that when the leaf 77 engages the inner face 51 of the control block 49, the leaf 77 moves away from contacting engagement with the upper leaf 81. The circuit to the solenoid 43 is therefore broken, the plunger 46 retracted, and with the arm 36 disengaged from the member 42, the shaft 28 is stopped with the tension adjustment bar 13 repositioned, being engaged at the wheel 23 by the tuning adjustment knob 25.

It is therefore clearly seen that a chord tuning mechanism is provided for a string instrument wherein one or more strings are automatically adjustable as to their tension, either singly or in combination, by the coaction between a set of shaft-operated electric switches, a shaft, and a pair of solenoids responsive to one or more of the switches. It is readily seen that the switch 66, for example, could be mechanically or electrically connected with a similar switch of another set of switches for another string, all similar to the structure 11. Then, upon closing switch 66 to effect a variance in the tension of the string 10 another or several other strings of the single instrument associated with string 10 could also have their tension affected, thereby effecting a new, predetermined chord without the fingers of the player's hand being placed on the strings.

65 I claim:

1. In a musical instrument having one or more tensioned strings disposed for audible vibration, means for progressively and selectively varying the tension of each string comprising in combination:

rocker means connected at one end to a string and operable upon being rocked to vary the tension on said string;

reciprocable means operatively connected to said rocker means and effective to rock said rocker means in response to reciprocation; and

manually controlled electric means for selectively reciprocating said reciprocable means.

2. In a musical instrument having one or more tensioned strings disposed for audible vibration, means for progressively and selectively varying the tension of each string comprising in combination:

rocker means connected at one end to a string and operable upon being rocked to vary the tension on said string;

reciprocable means operatively connected to said rocker means and effective to rock said rocker means in response to reciprocation;

drive means operable upon engagement to reciprocate said reciprocal means in a predetermined direction; and

manually controlled electric means for selectively operating said drive means.

3. In a musical instrument having one or more tensioned strings disposed for audible vibration, means for progressively and selectively varying the tension of each string comprising in combination:

rocker means connected at one end to a string and operable upon being rocked to vary the tension on said string;

reciprocal means operatively connected to said rocker means and effective to rock said rocker means in response to reciprocation;

a pair of arms independently connected to said reciprocal means;

drive means operable upon engagement by one of said arms to move said reciprocal means in one direction, and operable upon engagement by the other one of said arms to move said reciprocal means in an opposite direction; and

manually controlled electric means operatively engageable with said arms for selectively moving one arm into engagement with said drive means.

4. In a musical instrument having one or more tensioned strings disposed for audible vibration, means for progressively and selectively varying the tension of each string comprising in combination:

rocker means connected at one end to a string and operable upon being rocked to vary the tension on said string;

reciprocal means operatively connected to said rocker means and effective to rock said rocker means in response to reciprocation;

an electric circuit;

electromagnetic means interposed in said circuit and operable to effect reciprocation of said reciprocal means;

switch means interposed in said circuit and operable by engagement with said reciprocal means, said electromagnetic means activated in response to operation of said switch means; and

manually controlled electric means interposed in said circuit for effecting activation through said switch means of said electromagnetic means.

5. In a musical instrument having one or more tensioned strings disposed for audible vibration, means for progressively and selectively varying the tension of each string comprising in combination:

rocker means connected at one end to a string and operable upon being rocked to vary the tension on said string;

reciprocal means operatively connected to said rocker means and effective to rock said rocker means in response to reciprocation;

drive means adapted upon engagement with said reciprocal means to effect reciprocation thereof;

an electric circuit;

electromagnetic means interposed in said circuit and engageable with said reciprocal means for effecting engagement thereof with said drive means;

switch means interposed in said circuit and having a

normal first position, said switch means engageable by said reciprocal means and having a second position, said electromagnetic means responsive to said changes of position to effect movement of said reciprocal means; and

manually controlled electric means interposed in said circuit for effecting activation through said switch means of said electromagnetic means.

6. In a musical instrument having one or more tensioned strings disposed for audible vibration, means for progressively and selectively varying the tension of each string comprising in combination:

an electric circuit;

a manually operated normally open switch interposed in said circuit;

a rocker arm connected at one end to a string and operable upon being rocked to vary the tension on said string;

reciprocal means operably connected to said rocker arm and effective to rock said rocker arm in response to reciprocation;

drive means adapted upon engagement with said reciprocal means to reciprocate said reciprocal means in a predetermined direction;

electromagnetic means interposed in said circuit for moving said reciprocal means into and out of engagement with said drive means; and

switch means engageable by said reciprocal means for transmitting current from said switch to said electromagnetic means for effecting said reciprocal means movement.

7. In a musical instrument having one or more tensioned strings disposed for audible vibration, means for progressively and selectively varying the tension of each string comprising in combination:

a rocker arm connected at one end to a string and operable upon being rocked to vary the tension on said string;

a shaft operably connected to said rocker arm and effective to rock said rocker arm upon reciprocation of said shaft;

drive means engageable with said shaft to effect reciprocation thereof in either of opposite directions;

an electric circuit;

electromagnetic means interposed in said circuit and operable upon activation to move said drive means and said shaft into engagement with each other;

at least a pair of switches interposed in said circuit and having normal first positions, each of said switches selectively engageable with said shaft and thereby operable to attain respective second positions, each of said switches independently connected with said electromagnetic means and operable to activate said electromagnetic means.

8. In a musical instrument having one or more tensioned strings disposed for audible vibration, means for progressively and selectively varying the tension of each string comprising in combination:

rocker means connected at one end to a string and operable upon being rocked to vary the tension on said string;

reciprocal means operatively connected to said rocker means and effective to rock said rocker means in response to reciprocation thereof, said reciprocal means including a shaft having a switch block at one end thereof;

drive means engageable with said shaft to effect reciprocation of said reciprocal means in either of opposite directions;

an electric current;

electromagnetic means interposed in said circuit and energizable to effect selective engagement of said drive means and said shaft to provide movement of said reciprocal means in a predetermined direction;
